DESCRIPTION

This application is related to co-pending application Ser. No. 29/778,679, and to co-pending application Ser. No. 29/778,686, both filed on Apr. 14, 2021, the entire disclosures of which are incorporated by reference herein.

FIG. 1 is a perspective view of a sock in accordance with our design;

FIG. 2 is a right side view thereof;

FIG. 3 is a left side view thereof;

FIG. 4 is a top view thereof;

FIG. 5 is a bottom view thereof;

FIG. 6 is a front view thereof; and,

FIG. 7 is a back view thereof.

The broken lines show portions of the sock that form no part of the claimed design.

The portions shown in a pattern or patterns of stipple illustrate areas of contrasting appearance. The areas of contrasting appearance may be associated with different colors, different materials or combinations of materials, different stitching or other sock property.
